(57) **CLAIM**

The ornamental design for a set of fraction cards, as shown and described.

DESCRIPTION

FIG. 1 is a top view of a card of a set of fraction cards, showing our new design;

FIG. 2 is another card thereof;

FIG. 3 is another card thereof;

FIG. 4 is another card thereof;

FIG. 5 is another card thereof;

FIG. 6 is another card thereof;

FIG. 7 is another card thereof;

FIG. 8 is another card thereof;

FIG. 9 is another card thereof;

FIG. 10 is another card thereof;

FIG. 11 is another card thereof;

FIG. 12 is another card thereof;

FIG. 13 is another card thereof;

FIG. 14 is another card thereof;

FIG. 15 is another card thereof;

FIG. 16 is another card thereof;

FIG. 17 is another card thereof;

FIG. 18 is another card thereof;

FIG. 19 is another card thereof;

FIG. 20 is another card thereof;

FIG. 21 is another card thereof;

FIG. 22 is another card thereof;

FIG. 23 is another card thereof;

FIG. 24 is another card thereof;

FIG. 25 is another card thereof;

FIG. 26 is another card thereof;

FIG. 27 is another card thereof;

FIG. 28 is another card thereof;

FIG. 29 is another card thereof;

FIG. 30 is another card thereof;

FIG. 31 is another card thereof;

FIG. 32 is another card thereof;

FIG. 33 is another card thereof;

FIG. 34 is another card thereof;

FIG. 35 is another card thereof;

FIG. 36 is another card thereof;

FIG. 37 is another card thereof;

FIG. 38 is another card thereof;
FIG. 39 is another card thereof;
FIG. 40 is another card thereof;
FIG. 41 is another card thereof;
FIG. 42 is another card thereof;
FIG. 43 is another card thereof;
FIG. 44 is another card thereof;
FIG. 45 is another card thereof;
FIG. 46 is another card thereof;
FIG. 47 is another card thereof;
FIG. 48 is another card thereof;
FIG. 49 is another card thereof;
FIG. 50 is another card thereof;
FIG. 51 is another card thereof;
FIG. 52 is another card thereof;
FIG. 53 is another card thereof;
FIG. 54 is another card thereof;

FIG. 55 is another card thereof;
FIG. 56 is another card thereof;
FIG. 57 is another card thereof;
FIG. 58 is another card thereof;
FIG. 59 is another card thereof;
FIG. 60 is another card thereof;
FIG. 61 is another card thereof;
FIG. 62 is another card thereof;
FIG. 63 is another card thereof;
FIG. 64 is another card thereof;
FIG. 65 is another card thereof; and,
FIG. 66 is another card thereof.

It being understood that the rear is flat and unornamented and the side is of no substantial thickness.
